UNITED STATES PATENT OFFICE.

FREDERICK V. JONES, OF ZYLONITE, MASSACHUSETTS, ASSIGNOR TO THE ZYLONITE COMB AND BRUSH COMPANY, OF SAME PLACE.

DESIGN FOR A COMB.

SPECIFICATION forming part of Design No. 16,710, dated May 25, 1886.

Application filed April 5, 1886. Serial No. 197,894. Term of patent 14 years.

To all whom it may concern:

Be it known that I, FREDERICK V. JONES, a citizen of the United States, residing at Zylonite, in the county of Berkshire and State 5 of Massachusetts, have invented and produced a new and original Design for Combs, of which the following is a specification.

This design has for its object to provide a new and original toilet-comb which is ornamental and very attractive.

The design consists in a toilet-comb having the back to which the teeth are joined prolonged longitudinally into a handle in the form of the head of a dog, as shown, and hereinafter described.

In the accompanying drawing the figure is a side view of a toilet-comb made in accordance with my design.

Referring to the drawing, the numeral 1 in-

dicates the comb-back, to which the teeth 2 are joined. The comb-back is prolonged longitudinally at one end into a handle, 3, in the form of the head of a dog, which, as here shown, represents the head of a "setter" or "pointer" dog.

What I claim is—

The design for a toilet-comb having the back to which the teeth are joined prolonged longitudinally at one end into a handle in the form of the head of a dog, substantially as shown and described.

In testimony whereof I affix my signature in presence of two witnesses.

F. V. JONES.
